(57) **CLAIM**

The ornamental design for the cocktail shaker, as shown and described.

DESCRIPTION

FIG. 1 is a top perspective view of the cocktail shaker showing our new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom plan view thereof;

FIG. 8 is a top perspective exploded view thereof;

FIG. 9 is a bottom perspective exploded view thereof;

FIG. 10 is a top perspective view of a container portion of the cocktail shaker shown separately to show aspects of the design that are not visible when combined;

FIG. 11 is a top plan view thereof;

FIG. 12 is a front plan view thereof;

FIG. 13 is a bottom plan view thereof;

FIG. 14 is a top perspective view of a strainer portion of the cocktail shaker shown separately to show aspects of the design that are not visible when combined;

FIG. 15 is a bottom perspective view thereof;

FIG. 16 is a front view thereof;

FIG. 17 is a back view thereof;

FIG. 18 is a right side view thereof;

FIG. 19 is a left side view thereof;

FIG. 20 is a top plan view thereof;

FIG. 21 is a bottom plan view thereof;

FIG. 22 is a top perspective view of a lid portion of the cocktail shaker shown separately to show aspects of the design that are not visible when combined;

(Continued)

FIG. 23 is a bottom perspective view thereof;
 FIG. 24 is a front view thereof;
 FIG. 25 is a back view thereof;
 FIG. 26 is a right side view thereof;
 FIG. 27 is a left side view thereof;
 FIG. 28 is a top plan view thereof; and,
 FIG. 29 is a bottom plan view thereof.
 The broken lines in the drawings depict portions of the cocktail shaker that form no part of the claimed design.
